UNITED STATES PATENT OFFICE.

ALF SINDING-LARSEN, OF FREDRIKSVAERN, NORWAY.

TELEPHONE-TELEGRAPH.

SPECIFICATION forming part of Letters Patent No. 643,545, dated February 13, 1900.

Application filed August 22, 1899. Serial No. 728,064. (No model.)

To all whom it may concern:

Be it known that I, ALF SINDING-LARSEN, a citizen of the Kingdom of Sweden and Norway, residing at Fredriksvaern, Norway, have 5 invented certain new and useful Improvements in Telephone - Telegraphs; and I do hereby declare the following to be a full, clear, and exact description of the invention, such as will enable others skilled in the art to which 10 it appertains to make and use the same.

My invention has relation to telephone systems, and these as now generally organized present various inconveniences, one of which lies in the impossibility of advising a called 15 subscriber of the fact of having been called during his absence. To remedy this inconvenience, it has been proposed to combine a phonographic recording instrument with the telephone - receiver and provide suitable 20 mechanism for operating the recording-cylinder. In such an arrangement it is, however, necessary that the subscriber before absenting himself should switch the recording mechanism into the telephone-receiver circuit, and 25 should he omit to do so the recorder becomes useless. A further inconvenience and one that is often a very serious one lies in the possibility of the attendant at the central to obtain knowledge of all messages sent by one 30 subscriber to another.

My invention has for its object, first, to provide a telegraphic recording apparatus at each subscriber's station so organized as to require no attention should it be necessary 35 for the subscriber to absent himself or should he desire to obtain a telegraphic record of messages transmitted to him. My invention has for its further object the provision of means whereby the obtaining knowledge of 40 messages sent through the line by an attendant at the central becomes impossible.

To render practicable the combination of a telegraphic system with a telephonic system, the following conditions should prevail: 45 First, the transmission of telegraphic messages should in no manner influence the calling-off devices at the central; second, no means should be required for connecting the telegraphic recorder with the telephone system by hand; third, the telegraphic system 50 should be so organized as not to interfere in any manner with the use of the telephone

system in the ordinary manner; fourth, the telegraphic receiver or recorder should be so organized as to be applicable to existing telephone systems, and, fifth, the construction of the telegraphic receiver and its combination with the telephone system should be simple and cheap. 55

In the telephone system to be described and 60 embodying my invention all of the above conditions prevail. The first and second conditions are fulfilled by using a magnet as an armature for the indicator-magnet at the central and by using the call-magnet indicator 65 at the local stations as a transmitter for telegraphic impulses, means being provided for transmitting current impulses of one direction only when telegraphing a message, so that the armature of the indicator-magnet at the 70 central will remain uninfluenced, thereby rendering it impossible for an attendant at the central to obtain knowledge of a telegraphic message transmitted by one subscriber to another, and, finally, by providing 75 an auxiliary armature for the call-bell magnet acting as a circuit-closer for the telegraphic-receiver circuit. The fulfilment of the third, fourth, and fifth conditions is self-evident from the description of the two systems, reference being had to the accompanying 80 drawings, in which—

Figure 1 shows diagrammatically the combination of a telegraphic receiver or recorder with a telephone-receiver, the usual transmitter or microphone being omitted, it being unnecessary to a full understanding of my invention; and Fig. 2 is an elevation of the telegraphic receiver or recorder, its inclosing casing being shown in section. Fig. 3 shows 90 a record-strip in which the record is made crosswise instead of lengthwise.

Referring to Fig. 1, C indicates the central station, and S² and S³ two subscribers' stations, whose local circuits are connected at 3 3' with 95 the main lines 2 2', respectively. The circuits and appliances at both subscribers' stations being alike, I have indicated the same by like symbols of reference, distinguishing the parts at one station from those at the other by the addition of an affix to the said symbols.

M indicates the call-circuit magneto-inductor; m, the call-bell magnet; a, its armature;

b, the bell-clapper, vibrating when in operation between contacts *d* and *e*; *A*, the auxiliary armature of said call-bell magnet *m*, constructed in the form of a circuit-closing lever 5 for the circuit 30 of the telegraphic receiver or recorder *T*, and *S* indicates a switch-lever adapted to be moved into contact with the contact *f* or the contact *g*, said lever being normally in contact with *f*, and *R* indicates 10 the telephone-receiver, and *r* its switch-lever.

It being supposed that *S²* is the transmitting-station and *S³* the receiving-station and that the switch-levers *S* and *S'* at both stations are in contact with their respective contacts *f* and *f'*, this being shown in dotted lines at the transmitting-station, and the latter calls the central, current will flow from magneto-inductor *M*, via wire 4, to bell-magnets *m*, wire 5 to switch *S*, contact *f*, wire 6 15 to connection 3, line 2 to central, whereat the indicator-magnet will actuate its armature, and thereby the indicator drop, because alternating-current impulses are sent through the line. If now the central calls station *S³*, current will flow via line 2' to point 3', wire 6', contact *f'*, wire 5', bell-magnets *m'*, wire 4', magneto-inductor *M'*, wire 7', telephone switch-lever *r'*, wires 8' 9' to earth at *E'*, thereby actuating the call-bell. Should the subscriber 20 at the receiving-station be absent, or should he desire to have the message sent telegraphically and so recorded, he simply refrains from answering the call, and the central places the transmitting-station in communication with 25 the receiving-station, in which case the subscriber at said transmitting-station shifts the switch-lever *S* from contact *f* to contact *g*. If the sender now turns the crank of the magneto-indicator *M*, which crank for the purpose of telegraphing is provided, preferably, 30 with a small hand-wheel, current will flow as follows: from magneto-indicator *M*, via wire 4 to the call-bell magnets *m*, wire 5 to switch-lever *S*, contact *g*, bell-clapper armature *a*, and bell-clapper *b*. Should said clapper at 35 this time be in contact with contact *e*, the current impulse of one direction will flow from *e* to earth at *E* through wire 9. When, on the contrary, the clapper *b* is in contact 40 with *d*, the current impulse of opposite direction will flow through *b* *d*, branch wire 11, point 3, line 2, through the central station *C* to the receiving-station *S³* by way of line 2', point 3', branch wire 6', contact *f'*, switch *S'*, 45 wire 5', bell-magnets *m'*, wire 4', magneto-inductor *M'*, wire 7', telephone-switch *r'*, wires 8' and 9' to earth at *E'*. The current passing through electromagnets *m'* will energize the same, thereby causing circuit-closing armature *A'* to be attracted to close the telegraphic recorder circuit 30, as shown at station *S³*, and as it requires alternating currents to actuate the call-bell clapper *b'* the latter will remain 50 at rest for the reason that unidirected currents only pass through the coils, maintaining the magnets at the same polarity, so that when the armature *a'* is in its normal position of

rest, as shown, one end will be in contact with the magnet and remain so until a reverse current is sent through the spools. 70

Inasmuch as current impulses of one direction are conducted to earth and currents of opposite direction alone caused to flow through the line by the alternate shifting of the bell-clapper *b'* from contact *d* to contact *e*, 75 or vice versa, due to the alternating currents produced by the magneto-inductor, the armature of the indicator-magnet at the central will not be influenced by such direct-current impulses. Hence the attendant at the central 80 cannot obtain knowledge of the message transmitted by the means usually available.

The use of the magneto-inductor as a telegraphic transmitter simplifies the organization of the system very materially. Yet I desire it to be understood that I do not limit myself to such use, as a special transmitter could be included in the circuits without difficulty or in the circuit of a local battery, in which case all relay arrangements can be dispensed with, as direct-current impulses only would then be sent through the line. The same applies to the circuit-closing devices for the local circuits and to the combination with the bell-clapper of the contacts *d* and *e*, for 95 which devices special appliances could be substituted, though this would materially complicate the organization of the systems.

As regards the telegraphic receiver or recorder, it is preferably so organized as to be 100 operated by current impulses from a battery *B* in a local circuit 30, as shown. I am thus enabled to materially simplify the construction of the instrument, as shown in Fig. 2. Referring now to said Fig. 2, in the telegraphic recorder circuit 30 are included two electromagnets 21 and 31, the contact 29, the armature *A*, and the local battery *B*, Fig. 1. The armature 22 of the electromagnet 21 carries a tracer 23 or is otherwise constructed to trace upon or indent or cut code-symbols into a fillet of paper 33—as, for instance, Morse-code symbols—41 being the retracting-spring of said armature. 32 indicates the roll on which is wound a fillet of paper 33, that is guided over a revolute platen 24, the guide-roller 25, over a guideboard 34, and out of a slot 35 in the casing 36, containing the recording appliances. On a shaft 37 is secured a ratchet-wheel 16 and a gear-wheel 38 in gear with a transmitting-wheel 39, meshing with a pinion 40 on the shaft of the feed-roll 26 in frictional contact with the guide-roll 25. On the aforesaid shaft 37 is loosely mounted an armature-lever 14, whose shoe 13 is influenced by the pole 12 of the electromagnet 31, and said armature-lever has a short arm 17 projecting from its hub, adapted to engage a pin 18, projecting from a pawl-lever 15, loose on the arbor 37. To the lever 15 is pivoted a pawl 20, engaging the ratchet-wheel 16, and to the free end of said lever is connected a retracting-spring 19. It will thus be seen that at each closure of the circuit 30 the electromagnet 21 110 115 120 125 130

is energized and the armature-lever 22 attracted, thereby moving the style 23 out of contact with the paper fillet 33 on platen 24. At the same time the electromagnet 31 will 5 be energized and the armature-lever 15 will be attracted, thereby moving said armature-lever 15 against the stress of its spring 19, together with the pawl 20, a given distance from right to left. When the circuit is now interrupted, the electromagnets 21 and 31 are demagnetized, the spring 41 of the style armature-lever 22 will move the same into contact with the paper fillet on platen 24, the armature-lever 14 drops back into its normal position, and the spring 19 will draw the pawl-lever from left to right, thereby revolving the ratchet-wheel in the same direction and through the feed-gearing 38, 39, and 40 revolving the feed-drum 26, drawing the fillet 15 of paper along, and as the tracer or style is in contact with said fillet of paper a dot or a longer or shorter dash will be produced by the style in or on the paper fillet, according to the 20 length of time the style remains in contact 25 with said fillet of paper.

It will be seen that the character of the record-symbols—dot or dash of greater or less length—does not depend, as usual, on the length of time during which the circuit 30 mains closed, but on the length of time the circuit remains open between current impulses.

In the apparatus shown in Fig. 2 the symbols are formed lengthwise of the fillet of paper; but if the style were arranged to vibrate crosswise of the record-paper then the record would be produced in a like direction, as shown in Fig. 3.

Having thus described my invention, what 40 I claim as new therein, and desire to secure by Letters Patent, is—

1. In a telephone system, the combination with the main line, of a local receiver branch and a grounded signaling branch, an electromagnet in the latter branch, two armatures therefor, one actuating the signal and the other closing an independent circuit, a source of alternating current, and means for directing either alternating or unidirected currents 45 to line from an alternating-current source, and to receive either alternating or unidirected currents to operate the signal or the circuit-closer, substantially as set forth.

2. In a telephone system, the combination 55 with the main line, local receiver, and signal branches; of mechanism for closing an independent circuit, a grounded and a line-connected contact, a vibrating conductor, an armature and its magnet, said conductor and 60 armature adapted to direct unidirected cur-

rents from an alternating source to line to operate the circuit-closing mechanism at the receiving-station, and a hand phone-carrying lever adapted to ground either of the aforesaid branches, substantially as set forth. 65

3. The combination with the main line, the telephone-receiver and call-circuits and a local battery-circuit at a subscriber's station, the call-bell magnet, and means for transmitting or receiving through said magnet either 70 alternating or direct current impulses; of a telegraphic-receiver circuit an armature-lever operated by said magnet when energized by direct-current impulses to close the telegraphic-receiver circuit, for the purpose set 75 forth.

4. The combination with the main line, the call-circuit at a subscriber's station, the call-bell magnet, its armature, the bell-hammer actuated thereby, and the alternating-current 80 generator in said call-circuit; of a branch from the main line, having a contact-terminal, a ground connection having a like terminal between which terminals the bell-hammer is arranged to vibrate, whereby currents 85 of one direction may be grounded, and currents of an opposite direction sent to line, for the purpose set forth.

5. The combination with the main line, the telephone-receiver and call-circuits and a local battery-circuit including a telegraphic receiver at a subscriber's station, the call-bell electromagnet, a branch from the main line having a contact-terminal, a ground-line having a like terminal, the bell-hammer arranged 90 to vibrate between said contacts and the alternating-current generator in the call-circuit; of an armature-lever controlled by the call-bell magnet and operating to close the telegraphic circuit, whereby alternating currents, or currents of one direction may be caused to flow through said magnet, for the 95 purposes set forth.

6. In a telephone system, a local signal branch, signal-operating magnets included 105 therein, an auxiliary armature therefor, in combination with a local circuit adapted to be closed by said armature, a magnet operating a spring-retracted stylus, in series in said circuit with a second magnet, a platen, a train 110 of gearing operating a feed mechanism, said second magnet adapted to impart a step-by-step movement to the gearing, substantially as described.

In witness whereof I have hereunto set my 115 hand in presence of two witnesses.

ALF SINDING-LARSEN.
